FIG. 5

FIG. 1

FIG. 2

FIG. 3

FIG. 4

FIG. 1 is a side view of a fishing lure in accordance with one embodiment of the invention;

FIG. 2 is a top plan view thereof;

FIG. 3 is a bottom plan view thereof;

FIG. 4 is a front view thereof;

FIG. 5 is a rear view thereof;

FIG. 6 is a side view of a fishing lure in accordance with a second embodiment of the invention;

FIG. 7 is a top plan view of the second embodiment thereof;

FIG. 8 is a bottom plan view of the second embodiment thereof;

FIG. 9 is a front view of the second embodiment thereof; and

FIG. 10 is a rear view of the second embodiment thereof.

The characteristic features of my design reside in the combination of intersecting planes and in the hemispheri-

cal shape of the tail end with the upper of the planes being at a more shallow angle than the lower of the planes, the shallower plane extending rearwardly of the eyes.

I claim:

The ornamental design for a fishing lure, substantially as shown and described.
